F. S. COOK

CONVERTIBLE SCRUBBER STANDPIPE AND RETORT MOUTHPIECE

Filed April 24, 1924

Inventor
F. S. Cook,

By Clarence O'Brien

Attorney

UNITED STATES PATENT OFFICE.

FRANK S. COOK, OF HANCOCK, MICHIGAN.

CONVERTIBLE SCRUBBER STANDPIPE AND RETORT MOUTHPIECE.

Application filed April 24, 1924. Serial No. 708,822.

To all whom it may concern:

Be it known that I, FRANK S. COOK, a citizen of the United States, residing at Hancock, in the county of Houghton and State of Michigan, have invented certain new and useful Improvements in Convertible Scrubber Standpipes and Retort Mouthpieces, of which the following is a specification.

10 The present invention relates to improvements in coal gas retort standpipes, and mouthpieces, and has for its object to provide communication between the retort and standpipes, and to provide means whereby 15 said communication may be established or disestablished together with means for keeping the standpipes clear.

In the drawing:

Figure 1 is a view in elevation with parts 20 in section of the device assembled,

Fig. 2 is a side elevation of the upper portion of the stand pipe with parts thereof broken away and parts thereof shown in section, and

25 Fig. 3 is another side elevation of the standpipe, taken at right angles to the view shown in Fig. 2.

The lower end of the standpipe 1, enters 30 a trough 2, which is provided at one side with an outlet opening 3. A septum wall or baffle 4 is arranged transversely across the trough 2, at a point spaced from the outlet opening 3. The upper edge of the wall 4 is disposed in a plane above the plane, in 35 which the lower end of the standpipe 1 lies. The trough 2 may retain a volume of water, the level of the surface of which will be at the level of the upper edge of the wall 4, and whereby the lower end of the standpipe 40 1 is closed or sealed, by the volume of water retained in the trough. Any water in excess of such amount will flow over the upper edge of the sealing baffle 4, and make its exit from the trough 2 through the outlet opening 3 thereof.

At intervals along its vertical height, the standpipe 1 is provided with openings 5, which are normally closed by flexible plates 6. By removing the plates 6, the interior of

the standpipe 1 may be gotten at, for the 50 purpose of cleaning, or for removing obstructions therefrom, or for arranging the mechanism and means located therein. Thimbles 7 penetrate the side of the standpipe 1, at vertically spaced intervals, and each thimble may be connected with a retort. 55 Shafts 9 are disposed transversely across the standpipe 1, at points below the lower edges of the thimbles 7. Each shaft 9 is provided with an arm 10, which carries a plate valve 60 11, and this plate valve may close against the inner end of one of the thimbles 7, as best shown in Figure 2 of the drawings. Handles 12 are applied to the ends of the shafts 9, and are located exteriorly of the 65 standpipe 1, and may be used for turning the said shafts to move the plate valves 11 over the inner ends of the thimbles or to move said valves away from the said thimbles.

For washing or scrubbing the gases which 70 accumulate in a standpipe, during the operation of the retort, while producing gas, a cap 13 is provided, and is applied to the upper end of the stand pipe 1. A pipe 14 passes centrally through the cap 13, and is 75 connected with a seal 15, the terminal fold of which is provided with a funnel 16, which is upwardly disposed and in which water may be poured from the supply pipe S, for the purpose of feeding the same through the 80 manifold, into the pipe 14, and permitting the water to pass through the standpipe 1. A spreader 17 is connected with the pipe 14 and has an end portion disposed below and spaced from the outlet end of the pipe 14. 85 The said spreader is located within the standpipe 1, and the stream of water which falls from the pipe 14 strikes the spreader 17 and is broken into a number of fine streams, or is separated in the form of drops, 90 and these drops or streams descend through the gases, which have accumulated in the standpipe, washing the same, and carry the carbon and particles of solid matter, into the trough 2. Thus these gases are scrubbed, 95 and during the process of producing the gas in the retort, one or more of the retorts may be cut off from the standpipe by closing the

valve or valve plate 11, and at such time, the said retort may be discharged and recharged in the usual manner.

A dip pipe 20 is in communication with 5 the standpipe 1 and leads into an ordinary hydraulic main H for permitting the gas to flow from the standpipe.

Having described the invention, what is claimed is;

10 In apparatus for the manufacture of gas, the combination of a plurality of retorts, a stand pipe, means for establishing and dis-

establishing communication between the retort and the standpipe, a trough receiving the lower end of the stand pipe, a cap applied to the upper end of the stand pipe, a pipe passing through said cap, and a spreader carried by the last mentioned pipe and having an end portion disposed below and spaced from the lower discharge end 15 thereof.

In testimony whereof I affix my signature.

FRANK S. COOK.
